UNITED STATES PATENT OFFICE.

CLYDE E. COCHRAN, OF CLEVELAND, OHIO, ASSIGNOR TO THE ELWELL-PARKER ELECTRIC COMPANY, OF CLEVELAND, OHIO, A CORPORATION OF OHIO.

INDUSTRIAL TRUCK.

1,260,145.

Specification of Letters Patent. Patented Mar. 19, 1918.

Application filed November 10, 1916. Serial No. 130,518.

To all whom it may concern:

- Be it known that I, CLYDE E. COCHRAN, a citizen of the United States, residing at Cleveland, in the county of Cuyahoga and 5 State of Ohio, have invented a certain new and useful Improvement in Industrial Trucks, of which the following is a full, clear, and exact description, reference being had to the accompanying drawings.
- 10 This invention relates to trucks which have a propelling mechanism and a power-operated raisable platform. Such trucks, commonly called industrial trucks, are of great use in factories, ware-houses, freight 15 stations, etc., being adapted to be moved by power to bring the platform beneath goods suitably supported and then have the platform raised to pick up the goods with their support, the truck being then propelled to transport the load to any desired point, where it may be deposited by lowering the platform.
- 15 The object of this invention is to provide a simple, effective and powerful mechanism for raising and lowering the platform of such a truck. In its preferred form this mechanism consists of a screw connected with a platform which is supported on parallel links and a rotatable nut for the 20 screw, which is geared directly with the armature shaft of an electric motor. This gearing preferably consists of a worm wheel rigid with the nut and a worm rigid with the armature shaft. The motor, the gearing 25 and the screw are all mounted to swing as a unit about a horizontal axis transverse to the platform so that these parts may accommodate themselves to the various positions of the platform.
- 25 A convenient embodiment of my invention is illustrated in the drawings, wherein Figure 1 is a side elevation; Fig. 2 is a plan; Fig. 3 is a view in the nature of a plan on an enlarged scale of the motor and 30 mechanism connecting it to the platform; Fig. 4 is a section through the worm wheel and the worm with the motor shown in side elevation; Fig. 5 is a section along the axis of the screw which elevates the platform, 35 showing the motor in end elevation; Fig. 6 is an elevation of the brake mechanism,

looking toward the end of the motor casing; Fig. 7 is a sectional side elevation of the brake mechanism looking from the opposite direction of Fig. 4.

55

Referring briefly to the general construction shown, 1 indicates a front housing carrying a driving motor indicated at 2, and a battery therefor in a suitable box 3. Extending rearwardly from the lower portion of this front housing is a low lying skeleton frame 10. Suitably mounted on the sides of the housing are the propelling wheels 20, and carried by the rear frame are the wheels 21. The driving motor is 60 suitably connected with the propelling wheels 20 in any well known manner; thus, the motor may be connected by worm gearing (not shown) in the casing 4 with the rotary axles of the wheels. The motor is 65 controlled by a suitable controller indicated at 5, which is provided with an operating handle 7. The steering may be accomplished in any desired manner. For example, all four wheels may be steered, the 70 wheels being shown in Fig. 2 as connected by a system of cross links 24 and 25, and longitudinal links 26 and 27, with a steering column 28 (Fig. 1) operated by a hand lever 29.

80

It is to be understood that the general construction just described may be altered as desired. In the specific embodiment shown in the drawings, the sills 10 are secured at the front to upright frame bars 85 11 and at the rear to an axle 12. These sills are located at some distance within the outer edges of the platform, and may conveniently be channel beams, as shown. The front housing has other uprights 13 and 16 90 secured at their lower ends to extensions 17 of the sill frame. The sill frame is completed by pads 18 and 19 rigidly connected with the uprights 11 and 13. The housing also has two uprights 14 of channel shape 95 secured to the outer sides of the sills 10 and rising vertically at the rear end of the housing. All of the uprights are secured to the horizontal flanged plate 15 which carries the battery box. A vertical plate 16 forms 100 a rear wall for the housing and is secured to the uprights 14.

The arrangement described, of sills, uprights 11 and 13, and cross pads 18 and 19, provides a box-like space in which the front axle may rise and fall. The frame is 5 preferably supported by springs 23, between the pads 19 and the floating casing 22 of the axle, after the manner of a journal box of a railway car. The motor rises and falls with the axle, being connected with it by 10 the gear casing 4 and also by a brace 5 leading upwardly from the axle and connected at the upper end by a bracket 8 to the motor casing. This driving connection is simple, direct and compact, and the 15 spring suspension relieves the truck, and its load, of jars.

30 indicates the raisable platform. This is a horizontal member connected with the sill structure by parallel links 31 and 32. 20 There are two links 31 on the outer sides of the sills 10 and pivoted at their lower ends to brackets 33 which are secured to the sills and to the rear end of the front housing. The upper ends of these links are pivoted to 25 brackets 34 secured to the under face of the platform. At the rear I prefer to employ one link 32 which is mounted centrally beyond the sills and pivoted at its lower end at 36 to the stationary axle of the smaller 30 wheels, and at its upper end to the under side of the platform. These links 31 and 32 are shown as webbed for strength. They are of the same length and are parallel, so that as the platform moves it remains al- 35 ways horizontal, moving upwardly and toward the front as it rises and downwardly and rearwardly as it is lowered.

The motor, gearing and screw for elevating the platform is carried within the housing 1 in the space immediately in front of the upright posts 14 and beneath the support 15 for the battery box. 40 designates two inclined angle bars riveted at their upper ends to the posts 14 and extending down- 45 wardly and forwardly and riveted at their lower ends to one set of posts 11. Mounted on these diagonal bars 40 are bearing brackets 41. Into these brackets extend trunnions 42 carrying an oscillating frame 44. This 50 frame is hollow to provide casings for the screw, for the worm wheel and for the worm, the latter portion of the casing being extended to and being rigidly connected with the motor casing 49. Accordingly, the motor, 55 the gearing and the screw are all pivotally mounted by the trunnions 42.

It is desirable to have the above casing separable, to allow ready installation and access to the worm, for oiling, etc. Accord- 60 ingly, I prefer to make the casing for the worm wheel and nut in two parts. The main portion 46 of the worm wheel casing may conveniently be integral with the casing 47 for the worm, and with the casing 43, for

that portion of the screw between the nut and platform, as shown in Fig. 5. The projecting end of the screw is housed by a tubular casing 45 which extends from a plate 48 which is bolted to the casing 46. Suitable webs are provided to strengthen and stiffen 70 the parts of the casing which as shown may conveniently be made by two castings. The trunnions 42 may be studs screwed into the casing 43.

The screw 50 is shown clearly in Fig. 5. 75 It lies within the casings 43 and 45 and has a shank 53 extending out through a stuffing box 54 at the lower end of the casing. This shank is provided at its lower end with a head 56 which is connected by a pivot pin 51 80 with a bracket 58 secured to the forward end of the elevating platform 30. Within the casing 46 and threaded on the screw is a nut 60 which is shown as taking its thrust against a ball bearing 61 in the casing. This nut 85 carries at its outer edge teeth of a worm wheel. These teeth are on a ring 62 separate from the body of the nut but connected with it by a friction clamp consisting of a flange 64 on the nut and a ring 65, bolts 66 90 and nuts 68, and springs 67 compressed between the body of the nut 60 and the nuts 68. By these means sufficient friction is maintained at the clamp so that normally the worm teeth and the nut revolve as a unit, 95 but slippage is possible in case of an excessive load on the platform or other abnormal condition. The separation of the teeth and body of the worm wheel also allows the teeth to be made of bronze and the body of 100 steel, which is an advantage.

The worm for driving the worm wheel de- 105 scribed is designated 69. It is mounted in the casing 47, and meshes with the worm teeth 62, and is connected to the shaft of the armature. As shown in Fig. 4, the thrust of the worm is taken in either direction by a double ball bearing 68, mounted in the end of the worm casing 47. The other end of the worm is connected by a suitable coupling to 110 the armature shaft 81. This coupling is shown as consisting of a square extension on the armature shaft engaging a corresponding recess in the worm.

It will be seen from the above construction 115 that when the armature is revolved, the worm causes the nut to revolve comparatively slowly, which more slowly pulls up on the screw shaft 53 to elevate the platform. Oil for the worm gearing and for the nut 120 and screw are contained within the hollow casing, being retained therein by the stuff- ing box 54.

In operation the truck is usually backed to bring the platform under the goods to be 125 carried; then the raising motor is operated, which, through the gearing, nut and screw described, draws up on the shank 53 and ele-

vates the platform, swinging it upwardly and forwardly until the load is picked up; then the truck is driven to the desired position with the load in this condition, after 5 which the motor 49 is reversed and the platform is lowered to allow the load to descend onto a suitable support. The speed of the armature is preferably such that the load is quickly raised, the reduction in the gearing 10 giving the requisite power.

Any suitable means may be employed to open the circuit to the raising motor automatically when the platform reaches its uppermost or lowermost position, thus preventing 15 the motor driving too far. The slip connection in the worm wheel also protects the mechanism. As an additional protection I provide a magnetic brake which is held in idle position when the current is flowing 20 through the raising motor, but is automatically seated by spring action whenever the current is interrupted. Accordingly, whenever the current is off the brake is on. As the current is automatically 25 broken at the extreme positions of the platform, the operation of the raising motor is immediately stopped at these positions. The brake is located on the end of the motor casing opposite to the worm drive, and is shown 30 particularly in Figs. 6 and 7 and will now be described.

Secured directly to the end of the motor casing is a housing 70 formed with an annular recess to accommodate an annular winding 71 which is in series with the motor. The annular portions of the housing on opposite sides of this winding form north and south poles of a magnet. 74 indicates 35 a ring-like piece of metal which constitutes an armature for the magnet described. This armature is normally held distant from the magnet by means of springs 76 mounted in recesses in the housing and bearing 40 against the armature ring. Suitable studs 77 carried by the housing guide the ring. Secured at intervals on the ring are segmental linings 78 of suitable braking substance.

The springs 76 tend to press the armature 50 ring with the linings outwardly into contact with a disk 80 secured to the end of the armature shaft. This disk lies within a flange 79 of the housing 70. Normally the brake is held active by the springs 76, preventing 55 the armature revolving and thus holding the platform in a definite position. When, however, the current is turned into the raising motor the winding 71 is energized and the armature 74 is drawn inwardly 60 away from the disk 80 and this disk freed.

Having thus described my invention, what I claim is:

1. In a truck, the combination of a front

housing, a rearwardly extending frame, a 65 raisable platform mounted above said frame, a motor carried by the housing for raising the platform, a screw extending from a point within the housing to the platform, a nut within the housing on the screw, and 70 gearing between the motor and the nut.

2. In an industrial truck, the combination of a front housing, a rearwardly extending sill frame, a raisable platform over the extension of the sill frame, a battery box 75 within the housing, an elevating motor within the housing beneath the battery box, and a raising connection between said elevating motor and the platform comprising a nut and screw geared with the armature 80 shaft and connected to the platform.

3. In a truck of the character described, the combination of a truck frame and an elevating platform movably connected therewith, a hollow casing carried by the 85 truck frame, a screw and nut occupying the casing, the screw having a shank extending outside of the casing and connected with the platform, worm wheel teeth carried by the nut, a worm meshing with said teeth, 90 and a motor the armature of which is connected with the worm, the casing described being separable, one part carrying a housing for a portion of the screw and for a part of the worm wheel and the worm, and the 95 other part forming a portion of the worm wheel housing and having an extension forming a cap over the projecting end of the screw.

4. In a truck, the combination of a frame, 100 a raisable platform, a nut and screw, one member of which is connected with the platform, a motor for driving the other member of such connection, and an oscillating device carried by the truck frame, said motor being mounted on said oscillating device.

5. In a truck, the combination of a frame, a raisable platform, a screw connected with the platform, a nut for the screw, a motor 105 geared with the nut, and an oscillating frame carried by the truck frame and carrying the nut and motor.

6. In a truck, the combination of a frame, a raisable platform carried thereby, a screw connected with the platform, a nut for the screw carrying worm teeth, a motor, a worm meshing with the worm teeth and connected to the armature shaft of the motor, and a pivotally mounted casing carrying the nut, worm and the motor.

7. In a truck, the combination of a housing for a battery, a rearwardly extending frame, a raisable platform above said frame, a motor carried by the housing, a nut carried by the housing, gearing between the motor and nut, and a screw extending from said nut rearwardly and connected with the raisable platform, the nut,

gearing and motor being mounted to swing on a pivot as the platform rises.

8. The combination of a housing, a frame extending therefrom, a platform above the 5 extended portion of the frame, a casing pivotally carried in the housing, a screw within said casing, connected at its rear end to the platform, a nut within the casing engaging the screw, a motor bodily 10 movable with the casing, and gearing between the armature shaft of the motor and the nut.

9. In an industrial truck, the combination 15 of a front housing, a rearwardly extending sill frame therefrom, a raisable platform carried above the extension of the sill frame, a pair of bearings carried by the housing, an oscillating hollow frame having trunnions mounted in said bearings, a 20 screw connected with the platform and extending into the hollow frame, a nut within the hollow frame on the screw, a motor whose frame is rigidly connected with the hollow frame to move therewith, and gearing 25 connecting the armature shaft of the motor with the nut.

10. In a truck of the character described, the combination of a frame, a raisable platform connected therewith, a hollow casing 30 pivotally mounted on the truck frame, a screw, the lower end of which is pivotally connected with the platform, a nut for the screw, said casing having a chamber for the screw, and a communicating chamber for 35 the nut, a motor mounted on the casing to move therewith, and gearing between the armature shaft of the motor and the nut.

11. In a truck of the character described, the combination of a truck frame, an elevating 40 platform, parallel links connecting them, a hollow casing pivotally carried by the truck frame, a screw and nut occupying the casing, the screw having a shank extending outside of the casing and connected 45 with the platform, worm wheel teeth carried by the nut, a worm meshing with said teeth, and a motor the armature of which is connected with the worm, the casing described being separable, one part having 50 trunnions whereby it is pivotally mounted and carrying a housing for a portion of the screw and for a part of the worm wheel and the worm, and the other part forming a portion of the worm wheel housing and having 55 an extension forming a cap over the projecting end of the screw.

12. In an industrial truck, the combination 60 of a front housing carrying a battery, a sill frame extending rearwardly from the housing, a raisable platform above the sill frame, parallel links connecting the platform with the sill frame, a pivotally mounted casing within the housing, a nut within the casing, a screw extending from said nut

out of the casing diagonally downward and 65 rearwardly and pivotally connected with the front end of the platform, and a motor adapted to rotate said nut.

13. In a raisable platform truck, the combination of a hollow casing, a nut therein, 70 a screw connected with the platform extending into the casing and occupying the nut, a stuffing box carried by the casing and surrounding the shank of the screw, and a motor having its armature geared with the 75 nut.

14. In a truck of the character described, the combination of a raisable platform, a separable casing, a nut carrying worm-wheel teeth mounted in the casing, a worm 80 mounted in a communicating casing and meshing with said teeth, a motor having its armature shaft connected with the worm, a screw occupying the nut and extending out of the casing and pivotally connected with 85 the platform, and a stuffing box carried by the casing and surrounding the shank of the screw.

15. In a truck of the character described, the combination of a frame, a raisable platform 90 movably connected therewith, an oscillating casing mounted on the frame, a nut in the casing, a motor having its frame rigidly connected with the casing and its armature shaft geared with the nut, a screw occupying the nut and extending out of the casing, and connected with the platform, and a stuffing box carried by the casing and surrounding the shank of the screw. 95

16. In a truck, the combination of a truck 100 frame, a raisable platform, parallel links connecting them, a screw connected with the platform, a nut for the screw, a motor geared with the nut, and a slip connection in such gearing. 105

17. In a truck, the combination of a frame, a raisable platform, a screw connected with the platform, a nut for the screw, a ring having worm teeth frictionally carried by the nut, and a worm for driving 110 such worm wheel nut.

18. In a truck, the combination of a truck frame, a raisable platform, a screw connected with the platform, a nut on the screw, a ring at the periphery of the nut 115 having worm wheel teeth, an annular clamping device for frictionally clamping the ring on the nut, a worm meshing with such teeth, and a motor for driving the worm.

19. The combination, with a truck frame 120 and a raisable platform, of an oscillating frame, a motor and suitable mechanism both carried by said frame for raising the platform, and a brake for the armature bodily movable with the motor casing. 125

20. In a truck, the combination of a housing, a sill frame extending therefrom, a raisable platform connected with the sill

frame, a screw connected with the platform, a pivotally mounted casing carried by the housing into which the screw extends, a nut for the screw within the casing, a motor having its armature geared with the nut, said motor being carried by the casing to move bodily, and a magnetic brake carried

by the motor casing and bodily movable therewith and adapted to stop the rotation of the armature.

In testimony whereof, I hereunto affix my signature.

CLYDE E. COCHRAN.
